[57] CLAIM

The ornamental design for a printer, as shown and described.

DESCRIPTION

FIG. 1 is a front elevational view of a printer showing our new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a perspective view taken from the top, front and right side thereof;

FIG. 8 is a cross sectional view taken on line VIII—VIII of FIG. 1, with the interior construction omitted for clarity; and

FIG. 9 is another perspective view taken from the top, front and right side thereof.

The broken line representation of paper in FIG. 9 is for purposes of illustration only and forms no part of the claimed design.
